[57] **CLAIM**

The ornamental design for a bottle, substantially as shown and described.

DESCRIPTION

FIG. 1 is a perspective view of a bottle showing the new design;

FIG. 2 is an elevational view showing the side not seen in FIG. 1;

FIG. 3 is a view looking from the right of FIG. 2 the opposite side being the same in appearance;

FIG. 4 is a top plan view; and

FIG. 5 is a bottom view thereof.

*FIG. 1*FIG. 2

*FIG. 4**FIG. 3**FIG. 5*
